(57) **CLAIM**

The ornamental design for an in-car storage box set as shown and described.

DESCRIPTION

FIG. 1 is a perspective view of a first component of an in-car storage box set, shown separately for ease of illustration; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of a second component of the in-car storage box set, shown separately for ease of illustration; FIG. 10 is another perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; and, FIG. 17 is a perspective view of the in-car storage box set. The broken lines in the drawings depict portions of the in-car storage box set that form no part of the claimed design.
